DOOR LOCK MECHANISM

Edward I. Stulpin and Walter R. Hajdyla,
Detroit, Mich.

Application August 3, 1949, Serial No. 108,377

2 Claims. (Cl. 292—166)

1

This invention relates to an improved door lock mechanism and particularly to lock mechanism of the latch bolt type.

An object is to provide lock mechanism having a spring projected reciprocating latch bolt with simple plunger actuated means coupled therewith to retract the bolt counter to the action of a spring and with a simple lock pin to secure the plunger actuated means against movement so as to prevent release of the bolt.

A further object is to provide simple, inexpensive, rugged, easily installed and easily operable lock mechanism of the latch bolt type wherein there is a latch bolt held normally projected by a spring and wherein there is a plunger coupled with the latch bolt through a rockably supported bellcrank lever responsive to the depression of the plunger to be rocked thereby to actuate the latch bolt counter its spring, and wherein there is further provided a lock pin mounted for reciprocation and adapted in one position of reciprocation to engage one arm of the lever and prevent rocking movement thereof and adapted in another position of reciprocation to release the lever for rocking movement to actuate the bolt.

More particularly, an object is to provide lock mechanism wherein a latch bolt is reciprocably supported within a housing to be spring projected and a plunger is supported within a housing to be manually depressed and a bellcrank lever is swingably supported intermediate the plunger and the latch bolt, and so disposed as to be swung by depression of the plunger and so coupled with the latch bolt that upon depression of the plunger the latch bolt is retracted by the bellcrank lever; all characterized by the provision of a lock pin reciprocably mounted adjacent the bellcrank lever and having a part adapted, in one position of reciprocation of the pin, to be brought underneath that arm of the bellcrank which is in direct contact with the plunger to prevent rocking of the bellcrank lever. In the other position of reciprocation of the lock pin the bellcrank lever is released so as to be freely rocked by the plunger.

Other objects, advantages, and meritorious features will more fully appear from the following description, claims and accompanying drawing, wherein:

Fig. 1 is an elevation of a fragment of the edge of a door provided with our improved lock mechanism showing the same in elevation;

Fig. 2 is a sectional view taken on the line 2—2 of Fig. 1 showing a fragment of a door provided with our improved lock mechanism and showing the lock mechanism partly broken away and partly in section;

Fig. 3 is a cross-sectional view taken on the line 3—3 of Fig. 2;

Fig. 4 is a cross-sectional view partly in elevation taken on the line 4—4 of Fig. 2;

2

Fig. 5 is a fragmentary section through a modified form of construction; and

Fig. 6 is a sectional view on line 6—6 of Fig. 5.

This lock mechanism is particularly designed for use on communicating doors between rooms in a dwelling, as for example, a bathroom door. The lock mechanism is simple. It is made up of few parts. It can be easily installed. The latch bolt is easily retracted by a manually depressible plunger or button. Mechanism can be releasably locked from one side against actuation from the opposite side.

In the drawing let 10 indicate a door and 12 a door jamb member. The door jamb is provided with a striker plate 14 and a door stop 16. The door carries the lock mechanism. This lock mechanism comprises a latch bolt 18 supported within a housing 20 for reciprocation. The bolt is held normally projected by a spring 22. A stop pin 23 is provided. The housing is cut-away at the rear and the bolt itself is slotted transversely on opposite sides at the rear to receive the end of a rockably supported bellcrank lever 26. 28 indicates a retaining plate to secure the housing 20 in place.

The door is provided on opposite sides with latch bolt actuating mechanism in the form of a plunger 30 provided at one end with a thumb cap 33. This plunger is reciprocably supported within part of a housing 32 as shown in Fig. 2. Within this housing 32 the bellcrank lever 26 is pivoted upon a pivot pin 34, as shown in Fig. 2. One arm of this bellcrank lever has an end portion 36 which is received within the slot 24 of the latch bolt. The other arm of the bellcrank lever stands underneath the plunger pin 30 so as to be depressed thereby. It is apparent that depression of the plunger 30 will serve to swing the bellcrank lever to retract the latch bolt counter its spring 22.

There is also provided on each side of the door a handle portion 38 which may be secured to the door at one end as at 40 in any suitable manner. The opposite end of this handle member terminates in a barrel 42 which serves as a housing surrounding the plunger, as shown in Figs. 1 and 2. The casing 32 which carries the actuating mechanism may be secured to the door by screws or pins 44, as shown in Fig. 4. This casing 32 may be provided with flange parts 46 which are receivable within cut-outs in the body of the door, as shown in Fig. 3.

While only one assembly is shown complete in Fig. 2, it is apparent that two assemblies would be provided as illustrated in Fig. 1 and broken away portions thereof are shown in Fig. 2.

In the figures of the drawing there is shown on one side of the door only a lock pin which is adapted to be actuated to secure the mechanism against operation of the latch bolt. This lock

pin is indicated as 48. It is supported for reciprocation within the casing 32. It extends parallel to the latch bolt and substantially parallel to that arm of the bellcrank which lies directly underneath the plunger 30. Such pin 48 is cut-away on one side as at 50 providing a flattened portion terminating in end shoulders. The bellcrank lever which is engaged by the plunger 30 is notched as at 52 to seat upon one of these end shoulders when the lock pin 48 is projected to the position shown in solid line in Fig. 2. It is apparent that when the lock pin is projected to its opposite position of reciprocation that the bellcrank lever will be released to swinging movement, but when the lock pin is located as shown in Figs. 2 and 4 the bellcrank lever is held against swinging movement in response to urging of the plunger 30. A friction ring 49 of rubber or the like encircles the pin as shown in Fig. 2 being seated in a ring groove in the pin to hold the pin releasably at adjusted positions.

Figs. 5 and 6 illustrate a modification in which the construction is such that manual actuation of the plunger 30 serves first to withdraw the lock pin 48 and thereafter to swing the bellcrank 26 to withdraw the latch bolt. This result is accomplished by providing a modified form of plunger. Such plunger is cut-away or grooved on one side at its inner end as at 52 providing a shoulder 54 spaced from the bellcrank lever 26 as shown in Fig. 6, so as to permit slight inward movement of the plunger before the bellcrank lever is picked up. The plunger has an end extension which overlaps the bellcrank lever and which is itself beveled as at 56 to engage the shoulder 58 of the lock pin 48, as shown in Fig. 5, to retract the lock pin before the shoulder 54 of the plunger engages the bellcrank lever to swing it.

What we claim is:

1. Lock mechanism comprising, in combination, a latch bolt, a spring acting upon the bolt holding it normally projected, a plunger, a swingably supported bellcrank lever having one arm coupled with the bolt and the other arm disposed in proximity to the plunger to be actuated thereby to swing the lever to actuate the bolt counter to the action of said spring and a lock pin sup-

ported for reciprocation parallel to the plunger actuated arm of the lever, said pin having a part adapted in one position of reciprocation of the pin to engage said arm of the lever and hold the lever against swingable movement, said pin adapted in the opposite position of reciprocation to release the lever for swingable movement, said plunger so shaped as to provide a part which initially engages the lock pin to retract it before the plunger engages the bellcrank lever.

2. Lock mechanism comprising, in combination, a latch bolt supported within a housing for reciprocation, a spring holding the latch bolt normally projected, a plunger supported within a housing for reciprocation, said plunger having a laterally recessed flattened face extending from the inner end lengthwise thereof and terminating in a shoulder, a beveled surface on the inner end of the plunger, a bellcrank lever swingably supported having one arm coupled with the latch bolt and having its other arm disposed adjacent to the flattened surface of the plunger and substantially underneath the shoulder, a lock pin mounted for reciprocation substantially parallel to the latch bolt, said pin having a laterally recessed portion forming shoulders thereon, one shoulder at one position of reciprocation of the pin disposed to engage that arm of the bellcrank lever adjacent to the plunger thereby preventing swinging of the lever, said shoulder adapted also in such position to be disposed underneath the beveled end surface of the plunger to be engaged thereby to reciprocate the pin upon initial movement of depression of the plunger thereby releasing the bellcrank lever.
